Inventors:

Henry B. Newhall,
Henry W. Pleister,
By their Atty, Harold D. Penney

UNITED STATES PATENT OFFICE.

HENRY B. NEWHALL, OF PLAINFIELD, AND HENRY W. PLEISTER, OF WESTFIELD, NEW JERSEY; SAID PLEISTER ASSIGNOR TO SAID NEWHALL.

CABINET AMPLIFIER.

Application filed July 9, 1924. Serial No. 725,072.

Our present invention relates to an improvement in cabinets and has more particularly to do with an improvement in cabinets for sound producing or musical instruments, 5 and while my device may be found useful for phonographs and other instruments of this type, it is preferably adapted and applied to a cabinet for enclosing the customary radio receiver.

10 One of the objects of our present invention is to utilize in a cabinet of the character described a sound amplifier having great economy of space and lightness in weight and of great efficiency, and which due to its 15 construction is capable of forming part of the exterior wall of the cabinet and constituting in the present instance a door or closure member. Amplifiers suitable for this purpose are described and shown in pending 20 United States application Serial No. 668,840 filed Oct. 16, 1923 in the name of Harold D. Penney, and United States application Serial No. 695,974, filed Feb. 29, 1924 for improvements in sound amplifiers in the name of 25 Henry W. Pleister, both of which applications and the inventions therein described and claimed have been duly assigned to the above named Henry B. Newhall.

If reference is had to the two above noted 30 pending patent applications, it will be noted that one of the peculiar features of the structure of this sound amplifier as disclosed relates to its lack of depth, structurally speaking, and due to this feature, it is permissible 35 where used with a cabinet such as herein described and as shown in the drawings, to utilize the same as a door structure without encroaching to any material extent upon the space within the cabinet, thereby permitting 40 the effective and economical combination of a sound amplifying device with a cabinet enclosing a radio receiver of the customary type having the usual audio amplifying means and a loud speaking telephone within 45 the cabinet and without interfering one with the other and at the same time while producing amplified sound of suitable volume and quality, providing a portable amplifying cabinet of this class without materially increasing 50 the weight thereof and without interfering with the proper function of any of the coating parts and without the necessity for a cumbersome and unsightly amplifier or horn separable from the cabinet.

55 Another advantage of our device is that

owing to its narrow and shallow construction it may be readily adapted as a door in any desired position in a radio or other cabinet without necessitating any change in the hookup or assembly of the mechanism in 60 such cabinet other than merely substituting a shallow tone amplifier, of the type described, at any desired point in the cabinet.

Another advantage of our device relates to the manner of its connection to a cabinet and 65 the mounting of a device such as a loud speaker or other form of sounding device and the connection of these two to the amplifying section of a radio set or the like. The specific motive connection as herein disclosed 70 permits of easy opening and closing of the door to the interior of the cabinet, and permits easy inspection and adjustment of the interior mechanism of the cabinet when required.

75 In the accompanying drawings showing one of the possible embodiments of the invention:

Fig. 1 is a perspective view, and

Fig. 2 is a sectional view with the top removed, showing the door in section.

Similar reference characters denote similar parts throughout the several views.

Referring to Fig. 1, the cabinet comprises the usual housing for radio cabinets, the 80 front panel F having the usual dials D thereon for operating the coupler C and the condenser G, Fig. 2, and the smaller knobs K for operating the usual rheostats, the panel being provided with the usual bezels 85 B affording holes whereby to view the tubes during the operation of the set.

In the lower view, Fig. 2 represents the usual tube sockets and L the usual transformers, and it is to be understood that 90 while in Fig. 2 no attempt is made to combine or join these various coating elements in the well known manner, that this part of the showing of the invention may be of any standard type of hookup or assembly. In 100 the present instance, the receiver is preferably shown as a 3-tube set, one tube being a detector amplifier and the other two tubes being transformer coupled audio amplifier tubes whereby sufficient volume of 105 amplification may be had to operate any suitable or standard loud speaking magnetic telephone such as is indicated by M, Fig. 2, which may be any good type of loud speaking telephone.

As shown in Fig. 1 our amplifier or sound distributor comprises a comparatively shallow tone chamber, which in its preferable form comprises three elements, namely, the body portion 1 which may be of any suitable ornamental contour and arrangement as to finish. Preferably the body portion may be made rectangular as shown having a mid or central opening. Said body is of such proportions as will enable it to be used as one of the walls of the cabinet, and is here swingingly connected to an opening in the cabinet whereby to become a swinging wall or door portion rather than a fixed wall, though it is noted that the invention is not limited to swinging walls or doors. The door portion is shown swingingly connected therefore by means of a pair of hinges 2 of any suitable type, and provided with a latch or catch such as 3 whereby to latch the door shut when in use. The amplifying portion of the device consists of a primary annular convoluted disk of fairly large diameter generally denoted by 4 which is flexibly mounted on the door portion 1 by means of a resilient strip 5 which is affixed across the opening of the door portion at the rear thereof, and on the exterior side of the strip as indicated by the full line in Fig. 1, and by the dotted lines in Fig. 2. On the flexible cross strip 5 on the interior side thereof is mounted the telephone element M so that these last three elements are flexibly connected to and are movable with the door portion when it is opened or closed.

As a means for modifying or damping the tone volume without changing the setting of the radio receiver when once it has been set at its best point, there is provided a smaller or secondary deflector disk generally denoted by 6 in both figures and this in turn is mounted on the door portion 1, but independently of the other coacting tone parts of the device by means of an upright 7 fastened to the front portion 1 of the door and spaced away from the portion 1 by the bracket 8 or any other suitable means.

The upper end of the support 7 is provided with a fork carrying a thumb screw 9 and the secondary deflector 6 is provided with a stem 10 which is adjustably received in the fork 11 in such a manner that the deflector 6 may be shifted towards or away from the primary tone reflector 4 thereby cutting down the volume thereof without disturbing the quality of the sound, issuing therefrom.

It will be noted that the phone element M is connected by means of flexible conductive wire or cord N to one of the amplifying elements of the set while another wire N' may be connected to the B battery (not shown) in the usual manner and in this form of construction it is obvious that the amplifier described may be opened or swung outwardly

as indicated by the dotted position denoted by O so that access may be had to the interior of the cabinet without interference with any part of the active elements thereof.

It is also obvious from the foregoing that our improvement to cabinets of this type permits of the easy combination of this type of sound distributor as tone amplifying means to a cabinet and thereby effectually permits of a sound distributing means being usefully combined in a cabinet without increasing the cabinet size in any way, or without, as previously noted, interfering with the cooperating parts of the rest of the device, and obviating the necessity of transporting for use with the cabinet the customary cumbersome amplifier which must be separably connected to the cabinet, thereby creating a single combination of great portability and that a compact, ornamental and efficient combined cabinet and sound amplifying device is afforded.

Having thus described our invention, it should be understood that there may be modifications thereof and variations therein without departing from the spirit of the invention or exceeding the scope of the appended claims.

What we claim and desire to protect by Letters Patent is:

1. In combination, a cabinet having top, bottom, front, rear and end walls, the front wall having a door opening therein; an apparatus in said cabinet for producing vibrations; a sound distributor including a body fitting in said opening to form a door and hinged to one side edge of said opening and provided with rear opening, and a sound box mounted on said distributor and discharging sound into said rear opening and provided with a diaphragm and vibrating means therefor; said distributor, including said body and box, having relatively small front to rear dimensions; and freely flexible means connecting said apparatus with said vibrating means for transmitting vibration to said vibrating means when the door is closed, partly open or widely open for access to said apparatus, and permitting free opening and closing movement to said door.

2. In combination, a cabinet having top, bottom, front, rear and end walls, the front wall having a door opening therein; an apparatus in said cabinet for producing electric vibrations; a sound distributor including a body fitting in said opening to form a door and hinged to one side edge of said opening and provided with rear opening, and a sound box mounted on said distributor and discharging sound into said rear opening and provided with a diaphragm and electric vibrating means therefor; said distributor, including said body and box, having relatively small front to rear dimensions; and freely flexible conductors connecting

- said apparatus with said vibrating means for transmitting vibration to said vibrating means when the door is closed, partly open or widely open for access to said apparatus, and permitting free opening and closing movement to said door.
3. In combination, a cabinet having top, bottom, front, rear and end walls, the front wall having a door opening; radio apparatus in said cabinet for producing vibrations; a sound distributor including a body fitting in said opening to form a door and hinged to one side edge of said opening and provided with rear opening, and a telephone mounted on said distributor and discharging sound into said rear opening; said distributor, including said body and telephone, having relatively small front to rear dimensions; and freely flexible conducting cables connecting said apparatus with said telephone for transmitting electric vibrations to said telephone when the door is closed, partly open or widely open for access to said apparatus, and permitting free opening and closing movement to said door.
4. In combination, a cabinet having a substantially flat wall, an intramarginal door opening therein disposed a distance from the edges of the wall; and a sound distributor fitting in said opening to form a door and hinged to one edge of said opening and provided with an inner opening near the mid part of its inner face and an annular sound distributing chamber extending from said opening through the opposite outer face of the body; said distributor being adapted to receive a sound box mounted on said distributor and discharging sound into said rear opening; the main portion of said distributor including said chamber having relatively small front to rear dimensions equal to about twice the thickness of said wall and less than one sixth the diameter of the distributor.
- 45 5. In combination, a cabinet having a wall having a door opening therein; and a sound distributor fitting in said opening to form a door and hinged to one side edge of said opening and provided with a sound dis-
- tributing chamber including a sound receiving opening in its inner face and a large sound distributing opening in its opposite face; the distance between said faces being small relatively to the diameter of the door.
6. In combination, a cabinet having a wall having a door opening therein spaced from the edges thereof, and a sound distributor fitting in said opening to form a door and hinged to one side edge of said opening and provided with a sound receiving opening in its rear face and a large sound outlet chamber opening through its front face; said distributor being adapted to carry a sound box mounted on said distributor and discharging sound into said rear opening; said distributor having relatively small front to rear dimensions.
7. In combination, a cabinet having a substantially flat wall having a door opening therein spaced from the edges thereof; an apparatus in said cabinet for producing vibrations; a sound distributor fitting in said opening to form a door and hinged to one side edge of said opening and provided with an inner receiving opening and a large distributing chamber extending from said inner opening through the opposite outer face of the distributor, and a sound box mounted on said distributor and discharging sound into said rear opening and provided with a diaphragm and vibrating means therefor; said distributor, including said body and box, having relatively small front to rear dimensions less than half the diameter of the door; and freely flexible means connecting said apparatus with said vibrating means for transmitting vibration to said vibrating means when the door is closed, partly open or widely open for access to said apparatus, and permitting free opening and closing movement to said door while the vibration is being transmitted.

Signed at New York in the county of New York and State of New York this 2nd day of July, A. D. 1924.

HENRY B. NEWHALL.
HENRY W. PLEISTER.
